(57) **CLAIM**

The ornamental design for a tug toy substantially as shown and described.

DESCRIPTION

FIG. 1 is a front, left, top, 3D perspective view of the tug toy. FIG. 2 is a rear, left, top, 3D perspective view of the tug toy of FIG. 1.

FIG. 3 is a left side view of the tug toy of FIG. 1.

FIG. 4 is a right side view of the tug toy of FIG. 1.

FIG. 5 is a rear elevation view of the tug toy of FIG. 1.

FIG. 6 is a front elevation view of the tug toy of FIG. 1.

FIG. 7 is a top plan view of the tug toy of FIG. 1.

FIG. 8 is a bottom plan view of the tug toy of FIG. 1.

FIG. 9 is a front, left, top, 3D perspective view of a second embodiment of the tug toy.

FIG. 10 is a rear, left, top, 3D perspective view of the tug toy of FIG. 9.

FIG. 11 is a left side view of the tug toy of FIG. 9.

FIG. 12 is a right side view of the tug toy of FIG. 9.

FIG. 13 is a rear elevation view of the tug toy of FIG. 9.

FIG. 14 is a front elevation view of the tug toy of FIG. 9.

FIG. 15 is a top plan view of the tug toy of FIG. 9.

FIG. 16 is a bottom plan view of the tug toy of FIG. 9.

FIG. 17 is a left side view of a third embodiment of the tug toy.

FIG. 18 is a right side view of the tug toy of FIG. 17.

FIG. 19 is a top plan view of the tug toy of FIG. 17.

FIG. 20 is a bottom plan view of the tug toy of FIG. 17.

FIG. 21 is a left side view of a fourth embodiment of the tug toy.

FIG. 22 is a right side view of the tug toy of FIG. 21.

FIG. 23 is a top plan view of the tug toy of FIG. 21; and,

(Continued)

FIG. 24 is a bottom plan view of the tug toy of FIG. 21. The dashed lines illustrate portions of the tug toy that form no part of the claimed design. In FIGS. 17-24, the tug toy is shown with a symbolic break in its length. The appearance of any portion of the article between the break lines forms no part of the claimed design.

1 Claim, 24 Drawing Sheets
